UNITED STATES PATENT OFFICE.

AARON MENDELSON AND SHEPARD J. GOLDBERG, OF NEW YORK, N. Y.

CIGARETTE-BOX.

1,101,309.

Specification of Letters Patent. Patented June 23, 1914.

Application filed August 22, 1913. Serial No. 786,101.

To all whom it may concern:

Be it known that we, AARON MENDELSON and SHEPARD J. GOLDBERG, citizens of the United States, and residents of the city of 5 New York, borough of Brooklyn, in the county of Kings and State of New York, have invented a new and Improved Cigarette-Box, of which the following is a full, clear, and exact description.

10 This invention relates to an improved box for holding cigarettes or the like and consists in providing a box having hinged sections preferably of metal, with improved means within the box for holding the cigarettes.

15 Another object of the invention is to provide improved means of the character specified which is carried by one of the sections of the box and held in such position as to cause a plurality of independent cigarette 20 holders to be spaced apart in crossed relation when the box is open, whereby the cigarettes may be conveniently removed, whereas when the box is closed the sections 25 will be hinged in alinement and snugly fit within the box.

With the above and other objects in view, the invention resides more particularly in the peculiar combination and arrangement of parts which will be illustrated as a preferred embodiment in the accompanying 30 drawings and described in the specification.

Reference is to be had to the accompanying drawings forming a part of this specification, in which similar characters of reference indicate corresponding parts in all 35 the views, and in which—

Figure 1 is a perspective view of the improved cigarette box, with the sections opened out and the improved holders in supporting position; Fig. 2 is a longitudinal sectional view of the structure shown in Fig. 1; Fig. 3 is a cross sectional view of the box closed; and Fig. 4 is a cross sectional view of one of the holders.

45 In the illustrated form of the invention, the box is shown as comprising a pair of sections 10 and 11 which are provided with cooperating ears whereby they are pivoted by a pintle 12 permitting them to be readily 50 opened and closed in the manner shown in the drawings. Transversely supported in the section 10 near the pivot point thereof is a pivot rod 13 on which are mounted in spaced relation a plurality of holders 14. 55 These holders are preferably formed of single sections of sheet metal re-bent in U-form,

as shown in Fig. 4 of the drawings, providing back portions 15 and side portions 16 which are of a curvature to conform to the contour of the cigarettes 17 and also to grip the latter. To permit this, ribs 18 are formed in the side portions 16 adjacent to the back 15 and the edges and sides forming the gripping jaws and the holders are curved outwardly as shown at 19, while to add to the resiliency of the jaws elongated notches 20 are cut in the same so that the lower parts form sockets for receiving the cigarettes. The cigarettes are retained from displacement downwardly by the bottom portions 21 which have ears 22 formed at their rear ends for engagement with the pivot rod 13, there being suitable spacing means 23 in the form of a weak coil spring mounted on the pivot rod and between one of the outermost holders carried by the rod and the adjacent side of the section 10.

Pivoted through the spaced holders 14 is one leg of a substantially U-shaped frame 24, said leg also having intermediate holders 14' pivoted thereto and held in spaced relation to the holders 14 as by means of washers or other spacing means 25 located between each pair of holders, all of the holders opening in the same direction but the 75 holders 14' being mounted nearer their upper ends so that said latter ends will lie beneath the ends of the holders 14. The other leg of the holder 24 has the bottom portions of the holders 14' attached thereto by means 80 of ears 26 formed by curling the forward edges of the bottom portions of the holders 14' around said leg portion, in lieu of the rear portions as in the holders 14. The holders 14' are thus pivoted with respect to the 85 holders 14 and are held in crossed and spaced relation relative thereto by means of a coiled spring 27 which forms one spacing means, the coil of which is mounted on the upper leg of the support 24 and which 90 has one arm connected to the pivot rod 13 and the other operating against the back portion of the adjacent holder 14', so as to hold all of the holders 14 upward. A spring 28 is mounted on the pivot rod 13 between 95 the other side of the section 10 and the adjacent holder with respect to the position of the spacing means or spring 23 and has one arm contacting with the wall of the section 10 and the other arm contacting 100 with the back of the adjacent holder 14, thus retaining the holders elevated in the posi-

tions shown in Figs. 1 and 2 of the drawings. By closing the box sections the holders are caused to interlock or inter-fit against the action of the springs so as to be held 5 within the box in the manner shown in Fig. 3 of the drawings. By this construction the cigarettes will be held in position sufficient to prevent their accidental displacement but in such a manner as to permit them to be 10 readily withdrawn when the box is in open position, thus avoiding breaking of the cigarette, as results in removing the same from the boxes in the manner in which they are at present packed. The sections 10 and 11 15 may also be used as ash trays when the box is supported on a flat object, as shown in Fig. 1 of the drawings.

Having thus described our invention, what we claim as new and desire to secure 20 by Letters Patent is:—

1. The combination with a box; of holders carried within the box and means to cause the holders to move in spaced and crossed relation when the box is opened.
2. The combination with a box consisting of hinged sections; of a plurality of holders pivoted in one section, a plurality of holders pivoted to the last-named holders, and means to cause said holders to move into 30 spaced and crossed relation when the box is opened.

3. In a cigarette box, a pair of hinged sections, a pivot rod mounted transversely in one section adjacent to the pivot point thereof, a plurality of holders pivoted in spaced 35 relation on said pivot rod, a support pivoted to said holders, holders carried by the support and held in spaced relation to the first-named holders, means to hold the first-named holders out of the area of the section by which they are carried, and means to move said support and holders carried thereby in angular relation to the first-named holders.

4. In a cigarette box, a pair of box sections, a plurality of spaced holders pivoted in one section, a plurality of holders pivoted adjacent to the last-named holders and between certain pairs thereof, spring means normally elevating the holders, and spring 50 means normally holding the last-named holders in spaced relation to the first-named holders, all of said holders opening in the same direction.

In testimony whereof we have signed our 55 names to this specification in the presence of two subscribing witnesses.

AARON MENDELSON.

SHEPARD J. GOLDBERG.
